UNITED STATES PATENT OFFICE

FRIEDRICH von HEINRICH, OF BUDAPEST, HUNGARY, ASSIGNOR OF ONE-HALF TO
NATIONAL BANK OF HUNGARY, OF BUDAPEST, HUNGARY, A CORPORATION OF
HUNGARY

PROCESS FOR THE PRODUCTION OF GENUINE WATERMARK PAPERS WITHOUT USING
RELIEF MOLDS

No Drawing. Application filed October 15, 1931, Serial No. 569,113, and in Austria October 20, 1930.

Watermark papers have hitherto been made in most cases on sieves, bearing the watermark embossed in relief, the parts showing up dark in the paper forming the recesses, and the light parts in relief. For this purpose a wax relief was molded in accordance with the desired design, and representing the tone values of the latter as thinner or thicker portions when viewed by transmitted light. From this wax original, a negative electro was made, and from this latter a metal positive, a fine bronze gauze between the two being then submitted to such pressure as to transfer the projections and recesses of the wax original to said gauze. This fine sieve was then used as a paper forming mold.

Genuine watermarks were also produced by means of metal wire ornaments, script and the like soldered or welded to the sieves or screens. In this case, the watermarks are produced by the fact that at the places where the wire ornaments and the like are secured there is a decrease in water permeability and the relief portions of the wire cause a reduced deposit of the paper material. If the water permeability of relatively large areas of the screen is destroyed by the presence of these ornaments, etc., no deposit of paper material will occur at these places and holes will form in the paper web at the places where there was no deposit of paper material. If a paper web of this kind, i. e., one in which where paper actually formed the web is of uniform thickness and no watermark in the true sense of the word occurs, is placed on a second coherent web, the result is a patterned paper when viewed by transmitted light. In the production of multi-colored watermarks by the method just described, the first web is couched on a second, coherent, web of a different color. It has also been proposed to form watermarks in paper by means of a screen in which differences in water permeability thereof are produced by weaving the screen irregularly or by weaving thicker wires or patterns into the same on Jacquard looms.

According to the new process forming the subject of the invention, for the production

of gradations or half tones in the formation of genuine watermarks. I start with a photographic reproduction of the design of the intended watermark, and effect gradations in water permeability of the surface on which the paper is formed corresponding to the light tone values of the photographic reproduction. This procedure provides an entirely novel method of producing directly from a photographic half tone picture, watermarked papers which faithfully reproduce all tone values and fine gradations of the photographic original. To this end it is essential, according to the present invention, to decompose or break up the photographic half tone picture by means of a line screen, so that the light tone values of the half tone picture are represented by the relation between the covered and uncovered areas in the decomposed picture. If a paper forming surface be produced so that, corresponding to the picture decomposed by the screen, the covered areas are, say, the water permeable places and the uncovered areas are water impermeable, it will be apparent that the photographic half tone serves for reproducing the identical picture in the watermarked paper.

A great variety of forms of procedure may be followed in using a half tone picture to produce areas of differing water permeability in the paper forming surface. One of the simplest forms of procedure is to print with water insoluble inks or colors on a uniformly permeable material such as filter paper, textile fabrics, filter plates, etc.

If the paper forming surface for a water insoluble impression is to be made without the use of a uniformly water permeable base or foundation, so that the covered areas of the picture decomposed by the screen are to be holes which will bring about the difference in permeability in a compact substance such as metal, it is first necessary to effect the decomposition by means of the screen in such manner that the uncovered places of the decomposed picture will be united as in a grid. In some cases, it may be necessary to use a negative of the decomposed plate to achieve the desired connection of the surfaces. To

obtain the grid-like connection or interconnection of surfaces, the usual method of decomposing or breaking up half tone pictures may be employed. The resulting negatives, 5 capable of being etched, may be transferred by any well known method to thin metal plates or sheets which may be etched through where not covered with resist.

Such metal plates or sheets, which may 10 also properly be termed molds, may likewise be produced by applying to a metal plate by any suitable procedure (offset printing, copying, etc.) electrically insulating areas corresponding to the shape of the screen decomposed areas. If a separating layer has been applied to the virgin parts of the metal plate and the latter be used as a cathode in a galvanic bath, the resulting precipitate may be stripped from the plate as a mold with 15 parts differing in water permeability the electrically insulated parts appearing as holes. It is also within the contemplation of my invention to start with an electrically non-conductive surface, make a negative of the 20 previously used screen decomposition on, say, glass, and make the covered areas electrically conductive, these areas being covered in the galvanic bath with metal. In all cases, the resulting product is a metal plate with a coherent 25 surface, in which larger or smaller holes, corresponding to the photographic original and its light tone values, are so distributed that the water permeability of the sheet at its different parts is proportional to 30 the light tone values of the original at the respective parts.

In the production of paper forming surfaces it also, obviously, is possible to start with negatives representing various colors. 40 If the resulting molds for the production of half tone watermarked paper have correspondingly colored substances applied thereto and the colored half tone watermarked paper so produced is couched on a coherent, 45 compact, transparent base serving as a picture carrier, for example on paper, multi-colored watermarks result which when seen by transmitted light disclose colored pictures of the character of polychrome prints. 50 It will, of course be understood that the surfaces for producing the paper may be cylindrical in form, as is now the case with the present type of circular screen machines, and other modifications in the details of the 55 invention, within the scope of the appended claims, may be made without departing from the spirit of the invention.

Having now particularly described and ascertained the nature of my said invention, 60 and in what manner the same is to be performed, I declare that what I claim is:—

1. The herein described method of producing gradations or half tones in the watermarks of paper, comprising the making of a 65 photographic half tone reproduction of the

design to be used as a watermark, decomposing said reproduction by a line screen, and reproducing the said decomposed reproduction on a paper forming surface with the water permeability of said surface at various places proportional to the light tone values of the corresponding parts of the photographic reproduction, the water permeable and water impermeable parts of said surfaces corresponding with the resist covered and uncovered parts of the screen decomposition of the half tone picture.

2. The herein described method of producing polychrome watermarks in paper, comprising making a multi-color half tone reproduction of a colored design to be used as a watermark, decomposing said reproduction by a line screen, reproducing the said decomposed reproduction on correspondingly colored paper pulp supported by a coherent web serving as a picture carrier, and couching said pulp on said web to form colored watermarks which when viewed by transmitted light, correspond to the color and tone values of the colored design.

In testimony whereof I affix my signature.

FRIEDRICH von HEINRICH.
